MAGNETOSTRICTIVE PHONOGRAPH PICKUP

Filed April 17, 1946

UNITED STATES PATENT OFFICE

2,496,484

MAGNETOSTRICTIVE PHONOGRAPH
PICKUP

Frank Massa, Cleveland Heights, Ohio

Application April 17, 1946, Serial No. 662,791

14 Claims. (Cl. 179—100.41)

1

My invention is concerned with electro-mechanical transducers of the type in which vibrating mechanical motions may be converted to alternating electric currents, and, conversely, alternating electric currents may be converted to mechanical motions. This invention is primarily concerned with a phonograph pickup of the magnetostriction type and is a continuation in part of my patent application for Transducer means, Serial No. 588,691, filed April 16, 1945, now U. S. Patent No. 2,475,148.

As explained in the above patent application, the magnetostriction effect is the well-known magnetic phenomenon in which certain substances show a change in their magnetic properties when subjected to a mechanical strain. A reciprocal magnetostriction effect in these same substances causes their length to change when they are subjected to a change in magnetic field.

The purpose of this invention is to provide a means for efficiently employing the magnetostrictive properties of materials in the design of electro-mechanical transducers and, in particular, to produce a phonograph pickup which has performance characteristics superior to those shown by conventional electro-magnetic pickups and also in which the manufacturing cost is considerably less than the cost of such conventional pickups.

The conventional magnetic pickup generally employs a high permeability magnetic armature which is usually pivoted between one pair of pole tips and free to move between another pair of pole tips. The region within which the armature is free to move between a pair of pole pieces is usually of the order of a few thousandths of an inch, so that extreme care is necessary in the construction of the device as well as in the balancing of the armature so that the neutral position will remain exactly in the magnetic center of the pole pieces. As the magnetic armature is vibrated in its assembly, alternating flux is caused to flow through the armature which, in turn, induces a voltage within a small coil of wire which surrounds the vibrating armature which, in turn, furnishes the audio signal for operating the amplifier and associated phonograph equipment. The very nature of the design of the magnetic pickup requires precision production methods which result in relatively high costs. Due to the fact that a relatively high stiffness is necessary to keep the armature balanced and to prevent it from being attracted to one pole piece or the other, it is usually necessary to provide

needle forces of several ounces to permit satisfactory tracking of the needle in the record groove at the lower frequencies. This high stiffness which appears at the needle point induces greater record wear than would occur in a more compliant vibrating system.

The high cost of magnetic pickups, coupled with their higher tracking pressures, caused them to become superseded commercially by a Rochelle salt type of crystal pickup which has been produced at appreciably lower cost and permits greater compliance at the needle point than has been possible with the conventional magnetic pickup. In view of these advantages of the crystal pickup, it has found widespread application in spite of the fact that the structure is inherently fragile and suffers from temperature and humidity conditions that are normally encountered over portions of the United States. Another disadvantage of the crystal pickup, which is tolerated because of its lower cost, is its internally high electrical impedance requiring the use of a high impedance volume control that is generally less desirable than lower impedance control devices.

My phonograph pickup overcomes all the objections of the magnetic pickup and is also superior in every respect to the crystal pickup which has, up to now, widely replaced the magnetic units. My new pickup has a high enough needle point compliance so that satisfactory tracking results with a needle force of about one ounce. Its construction is such that a single air gap of the order of $\frac{1}{4}$ " may be used which eliminates all magnetic balancing problems as well as all expensive close tolerances in the assembly, and the efficiency is such that an output of the order of $\frac{1}{3}$ volt is produced at an impedance level of about 10,000 ohms. For constant velocity of the needle tip, my new pickup gives essentially constant output over the frequency range 50 cycles to 7000 cycles and the high-frequency range may be easily extended to higher frequencies for the few applications that may require it provided some sacrifice in output will be permitted.

The vibrating structure of my new improved pickup is a bi-metallic magnetostriction reed similar in principle to the transducer elements described in my aforementioned patent application. The physical constants of the reed structure that had to be developed to produce the desirable pickup characteristic will be described later in this specification. The mechan-

ical simplicity of the unit will be evident from a detailed consideration of the specifications which follow.

In the conventional pickups heretofore in general use, the needles have either been of the relatively heavy replaceable type held in position by a set screw or of the long-life, light-weight type wherein the needles are not easily interchangeable. One of the features of my new pickup is a light-weight, long-life needle tip that is easily replaceable by the user without resorting to the use of special tools or set screws.

An object of my invention is to produce a low-cost, magnetostrictive transducer that may be used for the conversion of mechanical motion into electrical energy, or for the conversion of electrical energy to mechanical motion over the normal audio-frequency range.

Another object of my invention is to produce a phonograph pickup which is much simpler to manufacture than the conventional magnetic pickups.

Still another object of my invention is to produce a phonograph pickup which will play phonograph records with so-called light needle pressures which are in the neighborhood of one ounce to one-and-a-quarter ounces.

Another object of my invention is to produce a pickup which is extremely rugged and not subject to variations due to climatic changes.

A further object of my invention is to provide an improved pickup design employing a long-life, light-weight needle tip which is easily replaceable by the consumer without the necessity of special tools.

Another object of my invention is to produce a phonograph pickup of improved performance characteristic such that high-fidelity reproduction may be obtained from high-quality disc recordings.

Still another object of my invention is to produce a phonograph pickup in which undesirable stray magnetic fields are neutralized to reduce hum therein.

The novel features that I consider characteristic of my invention are set forth with particularity in the appended claims. The invention, itself, however, both as to its organization and method of operation as well as additional objects and advantages thereof will best be understood from the following description of several embodiments thereof when read in connection with the accompanying drawings, in which—

Fig. 1 is a plan view of a bi-metallic, magnetostrictive reed that I employ in my new improved electro-mechanical transducer assembly.

Fig. 2 is an edgewise view of the reed of Fig. 1.

Fig. 3 shows the plan view of another type of bi-metallic, magnetostrictive reed in which one end is tapered to a smaller width.

Fig. 4 is an edgewise view of the reed of Fig. 3.

Fig. 5 shows a plan view of another bi-metallic, magnetostrictive reed in which one end is tapered to a smaller width in a somewhat different fashion than the taper shown in Fig. 3.

Fig. 6 is an edgewise view of the reed shown in Fig. 5.

Fig. 7 shows the mode of vibration of a thin, rectangular reed clamped at one end and driven at its fundamental resonant frequency at its free end.

Fig. 8 shows the mode of vibration of the same reed indicated in Fig. 7 when the free end is

driven at the frequency corresponding to its first overtone.

Fig. 9 shows schematically how mechanical damping elements are provided to prevent the mode of vibration indicated in Fig. 8 from being established.

Fig. 10 shows the free shape of one of the mechanical damping pads employed in Fig. 9.

Fig. 11 is a front-end view of a new improved phonograph pickup employing the teachings of my invention.

Fig. 12 is a side view of the same pickup indicated in Fig. 11.

Fig. 13 is a rear-end view of the pickup indicated in Fig. 12.

Fig. 14 is a cross-sectional view on a slightly enlarged scale of the pickup of Fig. 12 taken along the line 14—14.

Fig. 15 is an enlarged view of the end of the needle holder shown as part of the pickup of Figs. 11 and 12.

Fig. 16 is an enlarged view of the needle tip assembly as shown in Fig. 11 and Fig. 12.

Fig. 17 is a cross-sectional view through an improved phonograph pickup employing two of the basic structures indicated in Fig. 14.

Fig. 18 is a front-end view of the pickup shown in Fig. 17.

Fig. 19 is a schematic wiring diagram of the pickup of Fig. 17 and showing the coil arrangement and the mechanical arrangement of the vibrating elements to achieve the desired objective of eliminating hum pickup in the device.

Fig. 20 is a schematic view of a phonograph pickup embodying my invention.

Referring more particularly to Figs. 1 and 2, the reference character 1 indicates a bi-metallic assembly consisting of a magnetostrictively active element 2 bonded securely to another element 3. The portion 2 of the bi-metallic assembly may be either nickel or nickel-iron alloy having approximately 35 per cent to 60 per cent nickel, or cobalt-iron alloy having approximately 20 per cent to 70 per cent cobalt, which is described in my co-pending application Serial No. 588,691, filed April 16, 1945. The element 3 may be a magnetostrictively inert material, but is preferably a magnetostrictive material whose magnetostrictive effect is the negative of the effect existing in the magnetostrictive material 2.

A suitable combination, for example, would be to make the element 2 of nickel and the element 3 of nickel-iron alloy having approximately 35 per cent to 60 per cent nickel in its composition. Another satisfactory arrangement would be to have the element 2 nickel and the element 3 of cobalt-iron alloy having from 20 per cent to 70 per cent cobalt in its composition. The elements 2 and 3 are bonded together by any suitable method to

form the composite magnetostrictive element 4. In experimental tests which I have conducted, I found that the output of a phonograph pickup would increase several fold if the magnetostrictive element was completely annealed to the dead-soft state after fabrication.

Figs. 3 and 4 show a bi-metallic reed 4 which is built up from an assembly of portions 2 and 3 the same as described in connection with Figs. 1 and 2. The element 4 is tapered, as shown, whereas the element 1 is of uniform width throughout its length.

Figs. 5 and 6 show a bi-metallic element 5 which is also similarly constructed from components 2 and 3 in the same manner as described in Figs. 1 and 2. The element 5 differs from the element

4 of Fig. 3 in that the taper in element 4 results from removing material only from one side of the parallel edges as shown in Fig. 1, whereas the element 5 is tapered by removing material from each side of the parallel edges of the element 1 of Fig. 1.

The reason for having a taper as shown in Figs. 3 and 5 is that the effective mass of the vibrating system is reduced over the system of Fig. 1 at the higher frequencies. Another advantage of the taper results from the fact that the bending stress which is produced along the length of the reed when the free end is deflected is more uniform for the tapered system, thereby making each part of the tapered reed more uniformly active in the generation of voltage than would be the case in the uniform reed of Fig. 1.

Both elements of the bi-metallic assembly in Figs. 2, 4 and 6 are shown of equal thicknesses which would be desirable if each component material has the same modulus of elasticity. In such a case, by bending the free end of the reed, the boundary between the two component elements will remain unstressed and one element will be completely in tension while the other will be completely in compression. If the component elements are not of equal moduli of elasticity, the stiffer material should be thinner than the shifter material, such as indicated in Fig. 11 of my aforementioned co-pending application. The ratio of the thickness should be adjusted so that the boundary between the two elements remains unstressed during bending.

Fig. 7 illustrates diagrammatically the mode of vibration of a flat, rectangular reed 1 which is clamped at one end between the rigid blocks 6 and driven at the opposite free end at any frequency up to its fundamental resonant frequency. The fundamental frequency of a thin, rectangular reed which is clamped at one end, as indicated in Fig. 7, is given by the well-known expression

$$f_0 = \frac{.56t}{l^2} \sqrt{\frac{Q}{12\rho}} \text{ cycles per second}$$

where

t =thickness of reed in cms.,

l =free length of reed in cms.,

Q =Young's modulus of the material in dynes/cm.²,

ρ =density of material in grams/cc.

Fig. 8 shows the schematic representation of the mode of vibration of the same reed indicated in Fig. 7 at the first over-tone above the fundamental resonance of the reed. For a thin, rectangular reed, the first over-tone occurs at 6.27 times the fundamental resonance frequency.

In the conventional design of a vibrating system including a clamped reed, it is the general practice to so dimension the reed element that the fundamental resonance occurs at a frequency above the region within which the device is to be used. The reason for this procedure is to avoid deviations from the simple mode of vibration, as indicated in Fig. 7, and thus maintain uniform response over the frequency range of interest. If this procedure were followed in the design of my new pickup which will be described below, the stiffness of the clamped reed would be much too high to permit tracking of the pickup unless very high pressures were employed for keeping the needle in the record groove. This situation would be very undesirable both because of the abnormally high record and needle wear that would result and also because of the very

high noise that would be generated by the needle's scraping through the record grooves. In fact, the pressures would be so high that the pickup would be commercially inoperative. In the design of my new pickup, I find that in order to have a high enough compliance at the needle point so that tracking will be possible with a needle force of from one ounce to one-and-a-quarter ounces, and if the high-frequency response is to extend to the region 5 kc. to 8 kc., it is necessary to provide a reed thickness in the range $\frac{1}{2}$ mm. to 1 mm., and for such a condition, I found that the fundamental natural frequency of the vibrating system lies somewhere in the region within plus or minus one octave of 500 cycles.

I also found it possible to deviate from the preferred reed construction which has a fundamental resonance in the region within plus or minus one octave of 500 cycles, provided that either the output voltage were reduced and the high-frequency range extended beyond 8 kc., or provided the high-frequency range were limited to a value less than about 3 kc. For these special conditions, the resonance frequency of the vibrating reed could be as high as 2000 cycles for the former condition and as low as 200 cycles for the latter condition. When the fundamental resonance of the reed occurs in the lower audio range, it is obvious that the mode of vibration indicated in Fig. 8 will tend to be established somewhere along the higher portion of the audio reproduction range for which the pickup is intended, and if this higher mode of vibration were permitted to take place, the response of the pickup would not be uniform at the higher frequencies. In order to prevent the breaking up of the reed into the higher modes of vibration, such as indicated in Fig. 8, I employ a specially designed damping pad 11 shown in its normal shape in Fig. 10. The damping pad 11 comprises a simple flat spring 7 which is coated with a layer of soft, viscous material 8, such as a heavily plasticized vinyl resin or cellulosic resin.

Referring to Fig. 9, the reed 1 is anchored to a portion of a base 10 by means of the drive screws 9. Along each side of the reed 1 is a damping pad 11 held in position against the reed by the slightly flattened spring 7 which is mounted between the reed 1 and the base 10. The pads 11 are placed in such a manner that the soft, viscous material layer will be kept pressed against a portion of the reed 1. With such an assembly, I find that when the free end of the reed is driven at the higher audio frequencies, the modes of vibration, such as indicated in Fig. 8, are prevented from being established and, as a result, a pickup incorporating the vibrating system shown schematically in Fig. 9 gives a uniform response characteristic over the entire audio-frequency range for which the pickup is intended. The damping system shown in Figs. 9 and 10 also successfully prevents the torsional vibrational modes of the reed 1 that would tend to be excited at the higher frequencies as a result of the simplified needle drive system shown in Fig. 12. The torsional modes would tend to be produced because the needle point driving force is being applied along an axis off the center line of the reed as is evident from the construction in Fig. 12.

An alternative arrangement that I successfully employed to drive the reed consisted in pivoting the needle shoe 17 about half-way between the needle tip 20 and the reed 1 and attaching

the needle shoe to the end of the reed 1 only at a point near the center line of the reed. With such a pivot arrangement, no torsional modes were excited in the reed 1 which simplified the damping problem. However, the damping system as shown in Figs. 9 and 10 was capable of suppressing the undesired modes and produced a satisfactory pickup at a lower cost than would be required if the pivot drive system were adopted. It is, of course, obvious that the use of a pivot along the needle shoe can be employed in the construction, if desired, without deviating from the teachings of my invention. If the pivot is placed half-way between the needle tip and the drive point to the reed 1, there will be no change required in the design constants of the vibrating system. If the pivot causes the lever ratio between the needle tip and the reed to be different from unity, then the reed stiffness will have to be modified so that it is increased or decreased by the square of the lever ratio so that the resulting needle point compliance will remain the same as would have been the case with the unity lever ratio system. The effective transformation of the reed compliance to the needle tip by the square of the lever ratio is a principle well-known in the art of electro-acoustic transducer design.

An alternative method of damping that I found satisfactory was produced by substituting a piece of soft Vinylite (vinyl resin) tubing in the regions occupied by the members 11 in Fig. 10. Unless the tubes were cemented to both the surface of reed 1 and the walls of the structure 10, the soft Vinylite would cold flow in time and eventually not satisfactorily prevent the establishment of the higher modes of vibration of the reed. The use of the spring pressure in the pads 11, however, maintain continuous contact between the damping material and the reed without the necessity of using cements, thus achieving the desired objective in a cleaner and lower cost assembly. Still another type of satisfactory damping that I found consisted of providing a sponge-like mass of soft, viscous substance in the region between the reed 1 and the walls of the structure 10.

The actual design of a complete phonograph pickup, which has a uniform response characteristic up to about 6500 cycles when the needle tip is driven with constant velocity, is shown in the four views represented by Figs. 11, 12, 13, and 14. Referring to these figures, the reference character 12 indicates a molded, plastic structure which serves as a coil form, the mounting base for the magnetostrictive reed, the terminal board, and also as a support for the polarizing magnet. The structure 12 has a rectangular opening along its length shown best in the view of Fig. 14, and an off-set portion 13 shown in the views of Figs. 12, 13, and 14. Into the off-set portion 13 of the structure 12 are assembled the terminal pins 14 after the spool-like portion of the structure 12 is wound with insulated wire 15. The ends 15' of the coil of wire 15 are then soldered to the tips of the terminal pins 14. The off-set portion 13 has a plane surface to which the reed 1 is anchored by means of the drive screws 9. The plane surface is so located with reference to the rectangular opening along the length of the structure 12 that when the reed 1 is attached to the plane surface, the reed will be aligned along the center line of the opening. A pair of damping members 11, similar to those shown in Fig. 10, are inserted within the rectangular opening of

the structure, as shown in Fig. 14, following the arrangement described in connection with Fig. 9. A permanent magnet 16 is placed along the outer portion of the coil, as shown, and serves to send the necessary polarizing flux through the magnetostrictive reed assembly 1. I have found that when either nickel or 35 per cent to 60 per cent nickel-iron alloy is used as part of the reed structure, the optimum flux density necessary to produce maximum sensitivity and minimum distortion was less than 300 gauss in the air gap. Above 300 gauss, considerable distortion was observable in the electrical signal generated by the pickup.

To the free end of the reed 1 in Fig. 12 is attached a needle holder 17 which may be soldered or welded to the tip of the reed 1 preferably before the reed is assembled to the structure 12. A small piece of viscous damping material 18 is preferably cemented to the surface of the needle mount 17, as shown, in order to prevent any undesirable vibrational modes that might be established in the needle holder when the needle tip is operated by a phonograph record. Although not shown in Fig. 12, the damping material 18 may over-hang the needle shoe 17 and have part of the over-hanging portion secured to a fixed point such as the base structure 12.

The free end of the needle mount 17 is terminated into a formed cylindrical collar, shown enlarged in Fig. 15, which acts as a spring chuck into which a sleeve 19 having a collar 19', including a phonograph needle 20, as shown in Fig. 16, may be inserted and held. An outer housing 21 which may be formed in two pieces surrounds the pickup assembly with a layer of felt 22 or the like positioned between the housing and the inner assembly, and a pair of insulating bushings 22 are provided to prevent short-circuiting of the pickup terminals 14.

My new needle design permits the replacement of long-life needles by an unskilled user of the pickup without resorting to the complicated use of a soldering iron as is generally employed in present types of permanent-type pickups. Fig. 16 shows an enlarged view of the needle tip which comprises the needle 20 firmly assembled to a light-weight sleeve 19' which is preferably a plastic having a high ratio of modulus of elasticity to density, such as polystyrene. The needle 20 may be any of the several long-life types ranging from hard chrome-plated steel to sapphire tips, and the needles may be molded within the plastic sleeves. By the use of these molded needle assemblies, there is no appreciable mass added by the needle structure to disturb the performance or tracking of the pickup. It is also possible to make the sleeve 19' from either magnesium or aluminum with some sacrifice in performance due to the higher density of these metals compared with plastic.

Figs. 17, 18, and 19 show a pickup construction that eliminates the necessity for shielding the structure against stray magnetic fields. Referring to Fig. 17, two base structures 12 are mounted on a common base 25 by means of the screws 26. A reed 1 is assembled to each base structure 12 to form two identical pickups. The component elements 2 and 3 which make up the reeds 1 are so arranged that the similar elements such as 2 face each other when the assemblies are arranged as shown in Fig. 17, i. e., the magnetostrictive components of the bimetallic elements are arranged in opposite order. Common driving means 23 is attached to both of the reeds

1 and a common magnet 16 furnishes polarizing flux simultaneously through both of the reeds. A needle tip 24 is shown directly attached to the common driving means 23. The schematic wiring diagram for the two coils 15 is indicated in Fig. 19. For the coils connected, as indicated, any stray magnetic flux passing simultaneously through both of the reeds will induce equal voltages in the coils 15, and since they are connected in series opposing, as indicated in Fig. 19, the voltage across the terminals due to the leakage flux will be zero. When the needle vibrations cause the reeds 1 to vibrate, the voltage generated in the lefthand coil will be in opposite phase to the voltage generated in the righthand coil due to the fact that the elements 2 and 3 of the bi-metal assemblies are reversed, as shown in Fig. 17. Due to this phase reversal, the voltages induced in each of the coils 15 will be additive so that audio voltage will appear across the pickup terminals corresponding to the vibrations of the needle 24.

Fig. 20 schematically illustrates a magnetostrictive phonograph pickup in which two styli 30 and 31 are attached to the free end of the bimetallic element 1. In the position shown, the pickup is ready to play "hill and dale" recordings. The pickup head may be mounted in the pickup arm on a swivel arrangement which is not shown, so that a simple twist will cause a 90-degree rotation of the head, bringing the stylus 31 in a vertical axis and the pickup is then ready for playing lateral-cut recordings. The reference character 32 indicates a rigid anchor for the bi-metallic magnetostrictive device 1, and the reference character 33 indicates a permanent magnet which serves to send the required polarizing flux through the bi-metallic strip.

It is to be understood that the particular forms of apparatus shown and described, and the particular procedure set forth, are presented for purposes of explanation and illustration and that various modifications of said apparatus and procedure can be made without departing from my invention as defined in the appended claims.

I claim as my invention:

1. In combination in a phonograph pickup, a bi-metallic element one portion of which is magnetostrictive, means for rigidly mounting one end of said element, the other end of said element being free to vibrate in directions transverse to the axis of the element, means for producing a polarizing magnetic field through said element, and a coil surrounding said element, said element being characterized in that the total combined thickness of the bi-metal lies in the region $\frac{1}{2}$ mm. to 1 mm. and that its fundamental resonant frequency lies in the region within plus or minus one octave of 500 cycles.

2. The invention set forth in claim 1 further characterized in that said polarizing magnetic field is less than 300 gauss.

3. The invention set forth in claim 1 further characterized in that one portion of said bimetallic element is an iron-nickel alloy.

4. The invention set forth in claim 1 further characterized in that one portion of said bimetallic element is nickel.

5. The invention set forth in claim 1 further characterized in that one portion of said bimetallic element is composed of a magnetostrictive material in the dead-soft state.

6. The invention set forth in claim 1 further characterized in that damping means is provided in close proximity to the major portion of at

least one vibrating surface of said element, said damping means being a layer of viscous material and said close proximity between said viscous layer and said element being maintained by means of a bow-shaped flat spring whose convex surface presses the viscous layer against the surface of said element.

7. In a phonograph pickup, a hollow tubular coil form having a reed positioning portion adjacent one end thereof, one face of said reed positioning portion being located near and parallel to the center line of said tubular coil form, a coil wound about said coil form, a bi-metal magnetostrictive vibratile reed extending through said coil form substantially on the center line thereof, one end of the reed being attached to said face of said reed positioning portion, the other end of said reed being free to vibrate with respect to said coil form in directions transverse to the axis of the reed, said attached reed having a resonant frequency of less than 2000 cycles and more than 200 cycles, there being a gap within said coil form and about said reed, damping means disposed within said gap and engaging said reed and the interior of said coil form, and stylus means connected to the free end of said reed.

8. The invention set forth in claim 7 further characterized in that said stylus means includes a pivot about which said stylus means is made to rotate as the needle tip is vibrated, thereby causing translatory vibrations to be imparted to said magnetostrictive element.

9. In a phonograph pickup a hollow tubular coil form, a coil wound about said coil form, a permanent magnet disposed alongside the exterior of said coil and supported by said coil form, a bi-metal magnetostrictive reed, at least one element of which is composed of a dead-soft magnetostrictive material, extending through said coil form substantially on the center line thereof, one end of said reed being rigidly mounted with respect to said coil, the other end being free to vibrate with respect to said coil in directions transverse to the axis of the reed, stylus means connected to the other end of said reed, said reed being characterized in that the total combined thickness of the bi-metal lies in the region $\frac{1}{2}$ mm. to 1 mm. and that its fundamental resonant frequency lies in the region within plus or minus one octave of 500 cycles, there being a gap within said coil form on either side of said reed, and damping means disposed within said gap and engaging said reed, said damping means comprising a viscous substance in engagement with the sides of said reed.

10. In a phonograph pickup a hollow tubular coil form, a coil wound about said coil form, a bi-metal magnetostrictive reed extending through said coil form substantially on the center line thereof, one end of said reed being rigidly mounted with respect to said coil, the other end being free to vibrate with respect to said coil in directions transverse to the axis of the reed, and stylus means connected to the other end of said reed, said reed being characterized in that the total combined thickness of the bi-metal lies in the region $\frac{1}{2}$ mm. to 1 mm. and that its fundamental resonant frequency lies in the region within plus or minus one octave of 500 cycles, there being a gap within said coil form on either side of said reed, and damping means disposed within said gap and engaging said reed and the interior of said coil form, said damping means comprising a viscous substance held in engage-

ment with said reed by a spring engaging the interior of said coil form.

11. In a phonograph pickup a hollow tubular coil form, a coil wound about said coil form, a bi-metal magnetostrictive reed extending through said coil form substantially on the center line thereof, one end of said reed being rigidly mounted with respect to said coil, the other end being free to vibrate with respect to said coil in directions transverse to the axis of the reed, stylus means connected to the other end of said reed, said reed being characterized in that its fundamental resonant frequency lies in the region within plus or minus one octave of 500 cycles, there being a gap within said coil form on either side of said reed, and damping means disposed within said gap and engaging said reed and the interior of said coil form, said damping means comprising a viscous substance in engagement with the sides of said reed.

12. In a phonograph pickup a hollow tubular coil form, a coil wound about said coil form, a bi-metal magnetostrictive reed extending through said coil form, one end of said reed being rigidly mounted with respect to said coil, the other end being free to vibrate with respect to said coil in directions transverse to the axis of the reed, stylus means connected to the other end of said reed, there being a gap within said coil form on either side of said reed, said reed being characterized in that its fundamental resonant frequency is less than 2000 cycles and more than 200 cycles, and damping means disposed within said gap and engaging said reed, said damping means comprising a viscous substance in engagement with said reed throughout the major portion of the length thereof.

13. In combination in a phonograph pickup, a pair of bimetallic magnetostrictive vibratile reed-like elements, a coil surrounding each of said pair of elements, common means for the simultaneous driving of both said elements, magnetizing means for providing magnetic flux through each of said elements, the magnetostrictive components of said elements being arranged in opposite order, said coils being connected in series

opposition to each other, whereby the arrangement of said elements and the connection of said coils is such that the voltages induced in each coil due to the simultaneous vibration of the elements are additive whereas the voltages induced in each coil due to the presence of a stray alternating magnetic field are subtractive.

14. In combination in a phonograph pickup, a pair of laterally-spaced parallel bimetallic magnetostrictive vibratile reed-like elements, a coil surrounding each of said pair of elements, common means for the simultaneous driving of both said elements, magnetizing means for providing magnetic flux through each of said elements, the magnetostrictive components of said elements being arranged in opposite order, said coils being connected in series opposition to each other, whereby the arrangement of said elements and the connection of said coils is such that the voltages induced in each coil due to the simultaneous vibration of the elements are additive whereas the voltages induced in each coil due to the presence of a stray alternating magnetic field are subtractive.
